UNITED STATES PATENT OFFICE.

FRED KELLAR AND WILLIAM D. NEELY, OF NORTH VERNON, INDIANA.

SEPARATOR.

1,358,559.

Specification of Letters Patent.

Patented Nov. 9, 1920.

Application filed April 3, 1918. Serial No. 226,488.

To all whom it may concern:

Be it known that we, FRED KELLAR and WILLIAM D. NEELY, citizens of the United States, residing at North Vernon, in the 5 county of Jennings and State of Indiana, have invented new and useful Improvements in Separators, of which the following is a specification.

This invention relates to separators and 10 it has particular reference to a machine for separating cracked corn into a plurality of products, it being however, understood that the principles of the invention may be applied to the separation of other materials 15 into a plurality of products of different grades.

The invention has for its object to produce a simple and improved machine which at a single operation will separate a staple 20 into a plurality of products of different degrees of fineness.

A further object of the invention is to produce a machine of the class described of simple and improved construction which 25 will separate from the ultimate products, objectionable material such as dust and the like.

A further object of the invention is to simplify and improve a construction and 30 arrangement of parts constituting the improved machine or device.

With these and other ends in view which will readily appear as the nature of the invention is better understood, the same consists in the improved construction, novel 35 arrangement and combination of parts which will be hereinafter fully described and particularly pointed out in the claims.

In the accompanying drawings has been 40 illustrated a simple and preferred form of the invention, it being, however, understood that no limitation is necessarily made to the precise structural details therein exhibited, but that changes, alterations and 45 modifications within the scope of the claims may be resorted to when desired.

In the drawing,—

Figure 1 is a view in sectional elevation 50 of a machine constructed in accordance with the invention.

Fig. 2 is an elevation of the opposite side of the machine.

Fig. 3 is a sectional end elevation.

Fig. 4 is a similar view of the opposite end of the machine. 55

Fig. 5 is a top plan view, parts having been removed.

Corresponding parts in the several figures are denoted by like characters of reference.

The frame structure 15 of the improved 60 machine supports an upper screen cylinder 16 and a lower screen cylinder 17, the latter having a transverse partition 18 about midway between the ends thereof whereby it is divided in two sections *a* and *b* formed 65 of screen fabric of different grades, that of the section *a* being relatively fine. The partition 18 has in the lower part thereof an opening 19 establishing communication between the two screen sections. 70

Extending axially through the screens or sieves 16 and 17 and supported for rotation on the frame structure of the machine are shafts 19 and 20, said shafts being provided with pulleys or band wheels 21, 22 75 over which a belt 23 is trained to transmit motion from one shaft to another. Motion may be transmitted from a source of power to either one of the shafts 19, 20, each of said shafts being provided with a pulley 24, 25 over which a transmission belt may be trained. Said pulleys may be of different sizes in order that the speed may be varied by transmitting the transmission belt from one pulley to the other. 80

The frame of the machine supports the casing 26 of an aspirating fan, the shaft of which 27 is journaled in bearings 28, said shaft being provided with a pulley 29 that receives motion through the medium of a 90 belt or band 30 from a band wheel 31 on the shaft 19. The fan casing 26 is connected by a wind trunk 32 with the top portion of a settling chamber 33 having an inclined side wall 34 and a vertical side 95 wall 35 the latter being provided adjacent to its lower end with openings 36 for which doors 37, arranged to close gravitationally, are provided. The straight side wall 35 which adjoins the wind trunk 32 is provided adjacent to its upper end with downwardly inclined deflectors 38 that extend in the direction of a vertical deflector 39 which depends from the horizontal top portion 40 of the settling chamber. 100

Arranged below the cylindrical screen or

sieve 16 is a hopper 41 which receives material discharged through the screen and which discharges such material gravitationally through a chute 42. The screen cylinder 5 is provided at one end thereof, which for convenience will be designated as the outer end, with an inlet or feed spout 43 over which material is discharged from a source of supply into the upper portion of the 10 screen, the latter being provided at the inner end thereof and adjacent to its lower portion with an outlet spout or chute 44 over which the tailings are discharged into a duct 45 which communicates through a 15 trunk 46 with the settling chamber through the horizontal top portion of the latter. The duct 45 has a downwardly extending portion terminating in a discharge opening 47. Adjacent to the duct 45 is arranged a 20 feed chute 48, Fig. 3, with which it communicates through an opening 49 adjacent to which is pivotally mounted a valve 50 which, as shown in full lines in Fig. 3, may be utilized to obstruct the opening 49 but which 25 may also as indicated in dotted lines in the same figure, be utilized to obstruct communication between the spout or chute 44 and the discharge opening 47, thus establishing communication between the duct 45 and the feed chute 48. From the latter, material 30 may be discharged over a spout 51, see Fig. 1, to the inner end or receiving end of the screen or sieve 17.

Arranged below the sieve or screen 17 is 35 a hopper 52 having compartments a' , b' to receive material discharged through the screen sections a and b respectively, said compartments a' and b' being connected with the settling chamber by means of a duct 53 having a partition member 54 forming compartments 55, 56 having separate outlets 57, 58 Fig. 2 through which the products coming from the compartments a' and b' respectively will be discharged.

45 Adjacent to the tail end of the section b of the screen 17 is a discharge spout 59 whereby the tailings are delivered into a chute 60, said chute being connected by a duct or trunk 61 with the top portion of the settling chamber.

For the purpose of conveying stock 55 through the respective screens or sieves means are provided including arms 62 extending radially from the respective shafts 19 and 20, said arms carrying clamping bars 63 provided at intervals with clamp bolts 64. Clamped securely between each pair of bars 63 are a series of stems 65 each having at its outer end an angularly disposed wing 60 or blade 66 the outer edge of which will be disposed angularly with respect to the inner circumference of the screen, the position of the wings or blades relatively to the screen being capable of adjustment by turning the

stems 65 about their respective axes, thus being easily effected by slightly loosening the clamp bolts 64 while the adjustment is being effected. By rotation of the shafts 19, 20 material may thus be fed in either direction through the screens or sieves and by proper adjustment of the stems the wings may be variously spaced from the inner circumference of the screen according to the nature of the material that is to be operated upon. The brush members formed by the clamp bars 63 and related parts are found to be extremely simple and effective, not only in feeding material through the screens without unnecessarily rubbing the same, thereby producing dust and waste material, but the 75 brushes serving to feed material over the screens without contacting with the latter by simply rolling the material along, also serve to lengthen the height of the screens.

It is desired to be understood that the 80 screens, including the independent sections of the screens 17, are preferably mounted in such a manner as to be readily removable in order that screen sections of different 85 grades of material may be inserted and used when desired. Such adjustable mounting however, is well known in the art and is not herein claimed and it has not been deemed necessary to particularly illustrate such 90 mounting.

95 When the valve 50 is in the position shown in dotted lines in Fig. 3, the operation of the machine is as follows:

Cracked corn will be fed over the chute 43 to the receiving end of the screen 16. As 100 the stock passes over the screen by the action of the revolving brush member, a soft meal will be separated, the same passing through hopper 41 and spout 42 to the outlet of the latter where it may be discharged into a 105 sack or other receptacle. The tailings from the screen 16 pass over the chute 44 where it is immediately subjected to the action of the aspirating fan, bran and light dust being drawn to the settling chamber from which 110 it may be gravitationally discharged. The stock passing over the chute 44 will be guided over the valve 50, Fig. 3, which is then closed as shown by dotted lines, 115 through the opening 49 to the spout 51 at the lower end of the feed chute 48 being introduced by said spout 51 into the receiving end of the screen 17. In the compartments of said screen, two grades of grits or chicken feed will be separated, the two grades passing 120 through the compartments a' and b' of the hopper 52 to the compartments of the duct 53 where aspiration takes place, the grits being discharged gravitationally through the openings 57, 58 at the lower 125 ends of the compartments 55, 56 of the duct, while the dust and light materials will be carried through the trunk 53 to the settling

chamber to be gravitationally discharged therefrom. The tailings from the screen section *b* pass over the discharge spout 59 to the chute 60 where aspiration again takes place, the light products passing to the settling chamber while the resultant product being in the nature of pure cracked corn will be discharged through the opening at the lower end of the chute 60.

10 As a condition precedent to the operation described, the screen 16 employed will be, for instance, a screen of No. 16 wire, the screen *a* will be, for instance, a screen of No. 8 wire, and the screen *b* will be, for instance a screen of No. 6 wire.

A different result may be obtained by adjusting the valve 50 to the position shown in full lines in Fig. 3 and employing a screen 16 of No. 16 wire, a screen *a* of No. 26 wire and a screen *b* of No. 18 wire. The cracked corn first passes over the screen 16. The stock is conveyed over the screen by the brush, taking off fine dirt and dust which falls into the hopper 41 and is discharged 25 through the spout 42. The coarse stock tailing out of screen 16 over the chute 44 is subjected to aspiration when it enters the duct 45, the bran and dust passing through the trunk 46 to the settling chamber while the 30 stock is discharged through the opening 47 at the lower end of the spout 45. This material is now conveyed to a grinding device such as a grinding bur or roll, being ground into meal which is elevated and delivered

35 into the upper end of the feed chute 48 passing from thence over the spout 51 to the compartment *a* of the screen 17 where fine meal will be separated while coarse meal will be separated through the screen com-

40 partment *b* by the action of the revolving brush. The two grades of meal will be discharged through the openings 57, 58 of the compartments 55, 56 of the trunk 53, each grade being subjected to aspiration whereby

45 the dust and light material will be carried to the settling chamber. The over-tailings from the compartment *b* of the screen 17 will pass over the spout 59 to the chute 60 being there subjected to aspiration whereby

50 the light products are carried to the settling chamber while the relatively heavy material

will be discharged at the lower end of the spout 60.

What is claimed, is:—

1. In a separator, a frame structure, cylindrical screens supported at different horizontal levels, rotary means to work stock against and move the same longitudinally in the screens, a duct to convey tailings from the discharge end of the upper screen, a duct 55 to convey stock to the receiving end of the lower screen, said ducts being connected through an opening between intermediate portions thereof, and a valve arranged in one position to close the said opening and 60 in another position to guide stock from the first named duct into the second named duct.

2. In a separator, a frame structure, cylindrical screens supported at different horizontal levels, rotary means to work stock 70 against and move the same longitudinally in the screen, a duct to convey tailings from the discharge end of the upper screen, a duct to convey stock to the receiving end of the lower screen, said ducts being connected 75 through an opening between intermediate portions thereof, a valve arranged in one position to close the said opening and in another position to guide stock from the first named duct into the second named duct, a 80 settling chamber connected with the first named duct at a point above the connection between the upper screen and said duct, and an aspirating fan to set up suction in said settling chamber. 85

3. In a separator, a cylindrical screen, supporting means for the same, feed and discharge spouts supported adjacent to the ends thereof, a driven shaft extending axially through the screen, said shaft having 90 radial arms, side by side, clamp members carried thereby, clamping bolts associated with the clamp members, stems, fitted and movable about their axes between the clamp members, said stems being securely and adjustably held thereby, and wings, carried by said stems. 95

In testimony whereof we affix our signatures.

FRED KELLAR.
WILLIAM D. NEELY.
